UNITED STATES PATENT OFFICE.

MAX GARBELL, OF CHICAGO, ILLINOIS, ASSIGNOR TO VICTOR ADDING MACHINE COMPANY, OF CHICAGO, ILLINOIS, A CORPORATION OF ILLINOIS.

KEY-BUTTON ASSEMBLY.

Application filed November 13, 1926. Serial No. 148,246.

My invention relates to key button structures and methods of making the same, and it has particular relation to an assemblage of elements so constructed that they may be quickly and expeditiously related to each other in proper order by relatively unskilled labor.

I will hereinafter explain my invention in connection with a key structure or—as it is more familiarly termed in the typewriter art—"key button" which is used at outer or finger contact end of the key levers of typewriting, adding, and other machines employing designating characters which are struck by the finger to make an impression.

Such a key button assembly comprises a cup-member, in which the element bearing the letter or other indicia is placed, and a securing ring which is used to hold the latter element in place in the cup.

In most machines where such key buttons are employed, it is necessary that a row of characters be utilized, and therefore, the said characters must be carefully aligned to present a proper readable appearance. Moreover, care must be taken that the various characters are not placed in upsidedown position.

In those machines embodying key buttons and with which I am familiar, it has been necessary heretofore to expend considerable time in assembling the various elements to eventuate the desired results so far as alignment and proper positioning of the letter elements are concerned. The difficulties incident to this character of device will be more explicitly pointed out in connection with the description of my improved method, which latter may be best understood by reference to the accompanying drawing, in which:

Figure 1 represents a disassembled view in perspective of the elements utilized in my key button method;

Fig. 2 is a top view of the elements shown in Fig. 1 in their assembled relation;

Fig. 3 is an elevational, sectional view taken on the line 3—3 of Fig. 2;

Fig. 4 is a perspective view of the key button;

Fig. 5 is a disassembled view in perspective of the elements comprising a key button assembly of modified form; and

Fig. 6 is a cross-sectional view similar in character to that of Fig. 3, but in which the structure illustrated in Fig. 5 is shown.

Referring now more particularly to the drawings, a key lever 10 is provided at its outer or strikable end with an upstanding portion 11. Secured to the upper end of the portion 11, as by a riveted portion 12, is a character containing cup 13. A letter or character bearing member 14 comprises an upper portion 15 of celluloid, or similar material, bearing the character 16, and a lower portion 17 which is usually made of cork or other cushioning material, members 15 and 17 being secured together and comprising in effect one element.

My invention, therefore, contemplates the utilization of guide members or lugs which will at one time effect an initial correct positioning of the letter-bearing key buttons and also insure that said buttons are all in proper upright position. My improved assembly may be put together in correct and accurate alignment wholly by the sense of touch and without the need of further adjustment after the buttons are placed in the key cups.

To accomplish this end, I provide lug-like members 18 which are upset, or otherwise formed, on the inner surfaces of the upside walls of the cup. These lugs are made by dies so that they are invariable in position, which insures a correct alignment of the characters held by the cups. The characters, or buttons themselves, are provided with complementary grooves 19—19 so that an operator, no matter how unskilled, can only place the buttons in one position in the cups thereby effecting an absolutely correct alignment.

My invention is, therefore, of double advantage in that it permits the operator to very speedily assemble the key buttons and cup receivers in accurate alignment and at the same time does away with the necessity of turning the button after its initial placement, wherefrom the liability of damage in adjustment is entirely eliminated.

After the button 14 has been placed in the cup 13, an annular securing member 20 is put down over the cup 13 and the member 14 contained therein, resulting in an assembly as shown in Fig. 4. As heretofore suggested, my improved key button assembly not only permits of accurate alignment but may be so employed as to insure the correct positioning so far as up and down relation is concerned.

In Figs. 5 and 6 I have illustrated my invention as used in such a connection. There, only one lug or upset part 18 is utilized, and

this is placed at the outer side of the cup, that is, the side towards the operator of the machine on which the assembly is to be used. If now the character bearing element is provided with a groove 19 at its bottom only, an operator may, by the sense of touch entirely, place the button in the cup not only in correct alignment but with the assurance that the character has not been inserted in an upside down position.

I desire that the invention which I have described herein be interpreted in view of the prior art and that it be limited only by the scope of the appended claim since it is obvious that those skilled in the art may depart from

the structure shown herein while still utilizing the spirit of my invention.

I claim:

A key button assembly comprising a cup-like member positioned on the end of a key lever, positioning lugs struck inwardly from said cup member, and a character-bearing member having grooves formed in the side thereof to correctly co-operate with the positioning lugs in said cup to facilitate the assembly of said members.

In witness whereof, I have hereunto subscribed my name.

MAX GARBELL.
